PREFABRICATED BUILDING

Austin T. Levy, Harrisville, R. I.

Application March 4, 1937, Serial No. 129,093

7 Claims. (Cl. 72—1)

My invention relates to prefabricated buildings.

In such buildings utilizing walls including panels of insulating material having their edges in vertical and horizontal channel members presenting panel apertures, as described and claimed in my copending application Serial No. 105,721, filed October 15, 1936, it has heretofore been proposed to dispose the opposite ends of the vertical 5 steel rods carried on the opposite faces of the insulating panel board, within the upper and lower channels, and to connect these upper and lower channels and the panel board to the vertical channels by means of bolts extending 10 through the vertical channels forming part of the studs and through the horizontal channels and the panel board. In practice, however, this has resulted in difficulty, it being necessary for a quite exact alignment of the holes in the steel 15 channel members to be obtained in order to permit the bolts to be passed through the same. Further, by reason of limited space, in certain instances difficulty has been experienced in thereafter attaching the nut to the bolt and this has 20 of course in any event required an additional operation. Moreover, it has been necessary to provide a hole in the panel board for the passage of the bolt, which of course had to be brought into quite exact registry with this hole and the 25 holes in the several channels, and in some instances it has not been possible to attach the bolt at its inner end or to pass it through the edge of the panel board. As a result, the erection of such wall structures while using bolts 30 as connecting means, has involved considerable difficulty and delay and resultant expense.

My invention has among its objects to provide an improved construction including improved connecting means cooperating in a new 40 manner with the connected elements whereby it is made possible markedly to facilitate and expedite the operation of erecting such a wall, while substantially reducing the expense incident thereto and producing an improved wall structure. 45 A further object of my invention is to provide such an improved construction whereby the necessity for exact alignment of the several apertures is eliminated, and whereby since it is made unnecessary to attach a nut, it is also made possible to eliminate the difficulties heretofore experienced in connecting the nut in inaccessible 50 positions. A still further object of my invention is to provide an improved structure in which, while having these advantages, the connecting 55 means is also enabled to act as an aligning means

for the several apertures, and in which the connecting means, further being adapted to be driven through the panel board, makes it unnecessary to provide an aperture in the panel board before erection, while also enabling the panel board to be positioned by the connecting means under all conditions. These and other objects and advantages of my improvements will, however, hereinafter more fully appear.

In the accompanying drawing, I have shown 10 for purposes of illustration certain embodiments which my invention may assume in practice.

In this drawing:

Figure 1 is a perspective view of a wall assembly connected by my improved connecting means, 15 portions of the foundation being shown in section, an intermediate portion of the wall panels and studs being broken away, and the outer clinching wire and coatings of cementitious material being omitted, to facilitate illustration; 20

Fig. 2 is a sectional view on line 2—2 of Figure 1, showing the connection at the bottom of an intermediate wall stud;

Fig. 3 is a sectional view on line 3—3 of Figure 1, showing the connections at the bottom 25 and top of an intermediate wall stud, a portion of the completed wall here also being shown in section at the bottom to facilitate understanding, and

Fig. 4 is a view similar to Figure 2, but a section view on line 4—4 of Figure 1, showing the connection at the bottom of a corner stud.

In this illustrative construction, I have shown a wall structure including a foundation 1 carrying upwardly extending bottom channels 2 co-operating with oppositely disposed top channels 3. Also, a panel unit, generally indicated at 4 and comprising an insulating panel board 5 carrying spaced vertical rods 6 on the opposite faces thereof, is disposed with the top and bottom edges 35 of the panel board and the top and bottom ends of the rods 6 in the channels 2 and 3, while the vertical edges of the board 5 are disposed in vertical connected channels 7 which form the studs. Further, note that the several elements, comprising the channels 2, 3 and board 5, are connected to the channels 7 at the opposite ends of the latter by my improved connecting means.

Referring more particularly to Figure 2, it will be noted that the channel 2 receives therein the 50 oppositely disposed channels 7 of an intermediate stud in the relation indicated, spacer plates 8 preferably being disposed between the outer vertical walls of the connected channels 7 and the inner vertical walls of the channel 2 as in my 55

prior application. Here, however, instead of utilizing a pair of bolts extending through necessarily aligned apertures 9, 10, and 11 in the several metal channels and spacing strips, and 5 further providing an aperture in the board 5, all of which must quite accurately register with one another in order to permit insertion of the bolt, I herein provide improved driving pins 12 to connect the parts. Each of these pins 12 has a 10 pointed inner end 13 and any suitable head 14, herein an ordinary rivet head, on its outer end. Moreover, I drive this new pin 12 through the several apertures, the tapered end 13 thereof permitting the same to pass therethrough even if 15 they are not in exact alignment, and thereby permitting my pin 12 to function as a drift in bringing the apertures into the desired alignment. Moreover, it will be noted that the pointed end 13 makes it possible for the pin 12 to be driven 20 through the board 5 without requiring any previously formed aperture therein. Also the head 14 permits the pin to be quickly and securely connected by a quick and inexpensive welding operation to the outer vertical wall of the channel 2. Thus, with two such pins used in lieu of the two bolts and nuts heretofore used, it will be 25 noted that the parts may be very quickly and securely connected irrespective of the exact registry of the apertures and without requiring either 30 the provision of bolts or the use of nuts, or any connection to the inner end of the pin, while the welding of the head effectually unites the parts.

In connection with this construction, attention is also directed to the fact that the use of the 35 pin eliminates the previous need for setting any nut in the concrete, where, as in a preferred construction, the concrete 1 extends to the top of the inside of the vertical wall 2. Instead, my improved construction makes it possible for the pin 40 to be inserted in the channel before the panel unit is inserted therein and before the concrete is poured, in such manner as to close the adjacent aperture 9 in the channel and thereby during 45 pouring prevent the flow of concrete into the channel. Further, by using any suitable covering material for the pointed end of the pin, as, for example, wax, wood or the like, it is made possible after pouring to withdraw the pin whenever desired to permit the insertion of the panel, and 50 still readily reinsert the pointed pin in the aperture in the concrete when it is desired to connect the wall parts as heretofore described. Also, instead of using any such covering material, it will be evident that the pin may, if desired, be pushed 55 in before the concrete is poured, and that before the latter sets, the pin may be pulled out wholly or in part, in such manner as to leave the imprint of its pointed end in the concrete and thus also permit the ready later insertion of the 60 pin as a connecting means when later desired.

Referring to Figure 3, it will be noted that I have therein shown a pin 12 similarly inserted and welded and acting as a connecting means at the upper end of the stud 1, in addition to the 65 lower end connecting means heretofore described. Here, also, it will be understood that two such pins are used, as indicated in Figure 1, to connect the upper channel 3 to both of the channel portions 7 comprised in the stud. Of course, also, 70 no necessity existing for preventing the entrance of concrete into the channel 3 no necessity exists for inserting the upper pins before they are inserted in their connecting position during assembly.

75 In Figure 4, it will be noted that, while two

pins 12 are connected generally as heretofore described, these pins are of different length and used with a different construction of the corner stud. With the two channels 7 of the latter disposed at right angles to each other and mitered 5 and abutting as shown, it is obviously impossible satisfactorily to use a nut at the left hand or inner side of the right hand channel 7, or to use a nut and bolt with the bolt extending through the panel 5. However, it will be noted that by providing a shorter pin 15 and driving the same 10 through the panel, and welding the head 14 of the pin as heretofore described, it is possible to connect the parts very securely in the desired relation, while also enabling the shorter pin to pass 15 through the edge of the board 5 and thereby effectually position the latter.

In the use of my improvement, it is made possible not only to eliminate all need for providing nuts and bolts and substitute an inexpensive 20 spike therefor, but also very markedly to expedite and facilitate the process of erection, in such manner as also substantially to reduce the labor cost incident thereto. Thus, whereas, when inserting the bolts and nuts as heretofore, two 25 men have customarily been required, one on each side of the wall to cooperate in lining up the holes and holding the bolt while the nut is being tightened, my improved construction enables one man to insert and connect the pins, with a markedly 30 greater facility and despatch. Further, it will be evident that my improved construction is adapted to use under conditions which would not permit the use of a bolt and nut, i. e. where the nut could not be inserted or where the difficulty of inserting the same was such as to make 35 it impractical to use a nut. Attention is also directed to the fact that my improved construction is adapted to use not only in external walls as illustrated, but also in assembling internal partitions or wherever it is desired to connect a panel and its channels to channel studs. It will also be evident that, after assembly in the correct relation and the use of the pin as a drift in bringing the several elements into correct relation, the final step of welding the heads of the 40 several pins to the channels may be carried out very quickly and easily.

Here also it will, of course, be understood that after the assembly of the wall structure, the 50 latter is covered with suitable wire mesh 16 overlying the rods 6 and the exposed portions of the channels and the studs, and that this mesh is covered with stucco 17, forming the outer wall 55 surface, and plaster 18, forming the inner wall surface, as taught in my prior application mentioned.

While I have described certain embodiments which my invention may assume in practice, it will be understood that these forms of the same 60 are shown for purposes of illustration and that the invention may be modified and embodied in other forms without departing from its spirit or the scope of the appended claims.

What I claim as new and desire to secure by 65 Letters Patent is:—

1. In a prefabricated building, a panel, a panel positioning frame including vertical and horizontal members and having apertures in said members for receiving connecting means for said 70 members, and pointed connecting means for aligning said apertures as said connecting means is inserted.

2. In a prefabricated building, a panel, a panel positioning frame including vertical and hor- 75

izontal channel members one received within the other and having apertures in said members for receiving connecting means for said members, pointed connecting means for aligning said apertures as said connecting means is inserted, and means on said connecting means engaging the outer channel member.

3. In a prefabricated building, a panel, a panel 10 positioning frame including a horizontal channel member and a vertical channel member seated therein, said members having apertures therein for receiving connecting means for said members, a panel extending into said channels across said apertures, and means for aligning said apertures 15 and connecting said elements having a pointed end adapted as said means is inserted to align said apertures and form an opening in said panel, a shank disposed in said apertures and panel in the connecting position of said means, and a 20 head welded to the outer channel in said connecting position.

4. In a prefabricated building, a panel, a panel 25 positioning frame including spaced horizontal channel members and a vertical stud seated in channel members at its opposite ends and comprising 30 oppositely disposed channel members, a plurality of sets of aperture forming means in the overlapping portions of said channel members and stud for receiving connecting means at the opposite ends of said stud, and aligning and connecting means in said apertures having pointed 35 ends for aligning said apertures as said connecting means are passed therethrough, shanks extending through said apertures in connected positions, and outer ends engaging the outer channel.

5. In a prefabricated building, a corner stud 40 including angularly disposed connected channel members, a plurality of angularly disposed channel members cooperating to receive each end of said stud and each receiving a different channel member comprised in said stud, said stud and channel members having apertures therein at opposite ends for receiving connecting means, angularly disposed panels having edges received in 45 the angularly disposed channel members of said

stud and in said second mentioned channel members, and a plurality of pins disposed in said apertures having pointed ends for aligning said apertures, shanks extending through said apertures and panels, and heads engaging said second mentioned channel members. 5

6. In a prefabricated building, a corner stud including angularly disposed connected channel members, a plurality of angularly disposed channel members cooperating to receive each end of 10 said stud and each receiving a different channel member comprised in said stud, said stud and channel members having apertures therein at opposite ends for receiving connecting means, angularly disposed panels having edges received in 15 the angularly disposed channel members of said stud and in said second mentioned channel members, and a plurality of pins disposed in said apertures having pointed ends for aligning said 20 apertures, shanks extending through said apertures and panels, and heads fixed to said second mentioned channel members, one of said sets of apertures at each end of said stud providing a pin passage shorter than the other and also being obstructed by a part of said stud, and said pins 25 also being of different length.

7. In a prefabricated building, a foundation, a bottom channel fixed thereon in upstanding position and having oppositely located apertures in the inner and outer walls thereof, said foundation extending to the top of said inner wall, a stud including a channel seated in said bottom channel and having apertures adapted to register with said first mentioned apertures, a panel seated in said bottom channel and in the channel in said stud, a pin extending through said apertures and panel having a pointed end aligning said stud apertures with said channel apertures as said pin is inserted and extending into an aperture in said concrete beyond the inner 40 aperture in said bottom channel, and means on the opposite end of said pin from said pointed end welded to said bottom channel around the outer aperture therein. 35
